UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,559, dated January 7, 1890.

Application filed December 9, 1889. Serial No. 333,151. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular on the ground plan and comprises a first and second story. The front of the first story has a substantially flat exterior A. At one side of the flat portion A is a porch B, which extends along at the side of the residence. The side of the residence beyond the porch B presents a substantially flat

exterior C. To the rear of the portion C and at the back of the residence is a porch D. The second story of the residence is represented as overhanging the first story. Beneath said overhanging are consoles a. Gable roofs surmount the residence, the front of the house presenting a gable end G and the sides presenting a gable end H. The gables G H extend at approximate right angles to each other. The roof of the gable G extends downwardly to about the top of the porch B upon one side, but on the other side stops at about midway in the height of the second story. Both slopes of the roof of the gable H also stop at about midway in the height of the second story.

What I claim is—

The design for the exterior of a residence, substantially as herein shown and described.

WILLIAM K. BENEDICT.
